UNITED STATES PATENT OFFICE.

LOUIS PFINGST, OF BOSTON, AND SUMNER A. BEMIS, OF SPRINGFIELD, MASSACHUSETTS.

TRUCK FOR RAILWAY-CARS.

SPECIFICATION forming part of Letters Patent No. 449,382, dated March 31, 1891.

Application filed December 17, 1890. Serial No. 375,042. (No model.)

To all whom it may concern:

Be it known that we, LOUIS PFINGST and SUMNER A. BEMIS, citizens of the United States of America, residing at Boston and Springfield, respectively, in the counties of Suffolk and Hampden and State of Massachusetts, have invented new and useful Improvements in Trucks for Railway-Cars, of which the following is a specification.

10 This invention relates to trucks for railway-cars, the same being especially designed for street-railway, electric, or cable cars; and the object of the invention is to improve the construction of the truck whereby the truck is of unusual efficiency.

15 The invention consists in the construction and combination of parts, all substantially as will hereinafter more fully appear and be set forth in the claims.

20 Reference is to be had to the accompanying drawings, in which the invention is illustrated.

Figure 1 is a plan view of one side half of the truck, while Fig. 2 is an elevation of same. 25 Fig. 3 is a perspective view of the sill-plate for the car. Fig. 4 is a perspective view of one of the yokes of the truck-frame. Fig. 5 is a perspective view of the axle-box; and Fig. 6 is a central longitudinal vertical section and 30 partial elevation of a portion of the truck, the relations with said truck portions of the journal-box being indicated in dotted lines.

In the drawings, A represents the yoke or truck frame, the same comprising at each 35 side of the truck a longitudinally-ranging yoke-beam, each consisting of a pair of yokes *a a* and the intermediate and uniting-beam *b*, which beam, as here shown, consists of the paired bars which by their ends are bolted to 40 the extensions *a'* of the side pair of yokes which are toward and nearest to each other. B represents the journal-box which is of a construction common in trucks already constructed by us, the same being provided with 45 the forwardly and rearwardly extended steps *c c*, socketed in their upper sides, and also vertically apertured, as at *d*. The yoke is of peculiar construction, being designed to have certain portions thereof cushion-supported 50 from the axle-box steps, and also to serve as a hood or inclosure for the axle-box, and as

particularly shown in Figs. 4 and 6, the whole is integrally formed or cast with the extensions *a'* and *a''*. The yoke is provided with an aperture *e*, transversely thereof and extending from a short distance below the top thereof to the bottom, and is provided between the opposing cheek-pieces *2 2* in pairs, forward and to the rear of said aperture, with the horizontal rests *f f*, which are cast as webs, 55 transversely uniting the pairs of cheek-pieces forward and to the rear of said aperture *e*, and in the setting up of the truck the said rests *f* are supported a short distance above the journal-box steps *c c* by the cushions or springs 60 *g g*. The cheek-pieces *2 2* are upwardly continued above the said aperture *e*, and merged together, or the one into the other, as at *h*, in the form of a dome or hood overlying and inclosing the axle-box proper, the steps 70 of said axle-box being inclosed within the lower portions of the said cheek-pieces *2 2*. It is also preferred to interpose a spring or cushion *i* between the top or roof of the yoke and the top of the axle-box proper, as 75 most clearly shown in Fig. 6, and in this connection it will be seen that there is a supplemental cross-web *j* below the top of the dome-shaped yoke, suitably re-enforced for the necessary strength to withstand the resistance 80 offered thereagainst primarily from the top of the box.

It will be seen, noting Figs. 4 and 6, that the yoke is cored out internally between the rests *f* and the top of the yoke, as well as below the said rests, which latter coring-out or open construction is necessary for the accommodation of the steps *c* of the axle-box, while the hollow construction at the top of the yoke is for avoiding unnecessary weight, 90 it being entirely practicable to provide under the design and construction illustrated a yoke which is practically a shell, and yet is sufficiently rigid and strong. The pending portions 88 of the pairs of cheek-pieces, which 95 are forward and to the rear of the separating-aperture *e*, are united by the tie-braces *q*.

C represents the sill-plate, which is provided on the under side of the sill of the car-body above each axle-box of the truck, and 100 comprises a main bearing-plate *k*, adapted by bolts 33 to be secured to the sill, and is pro-

vided with sockets 7 7, formed as depressions within its under side for receiving the extremities of the bolt-rods *l* and the nuts *m*, which are employed for effecting an engagement between the sill-plate and the tie-beam *D*, to be hereinafter more particularly mentioned, the engagement of said bolt-rods with the sill-plate in no manner necessitating boring or in any manner recessing and consequently weakening the car-sill, it being noted that the extremities of the said bolt-rods *l* and the confining-nuts therefor are sunk within the top surface of the sill-plate. The said sill-plate outside of said bolt-rod connections—that is, toward the ends of the sill-plate from said connections—is provided with a pair of downwardly-extended bosses socketed from their under sides, as at *n*, and it will be noticed that the yoke-extensions *a'* and *a''*, directly under said sockets *n*, are of cup or socketed form, as at *n' n'*, the springs *o* being interposed between the sill-plate and yoke, said springs resting by their extremities in the said upper and lower sockets *n* and *n'*.

25 The said bolt-rods *l l* pass through apertures 5 5 in the top of the domed or hooded yoke, through the apertures 6 6 in the rests *f f* of the yoke, through the apertures *d d* of the journal-box steps to and below the under side 30 of said steps for a suitable distance, the cushions *g g* being also perforated to permit the passage through them of the said bolt-rods, and, particularly noting Fig. 2 as well as Fig. 6, it will be seen that the tie-beam *D* is bolted to and suspended upon the lower ends of the said bolt-rods *l l*, serving also as braces to tie the said pairs of the bolt-rods adjacent each journal-box together, and to maintain them in parallelism and materially strengthening or stiffening the structure. It is also deemed desirable to provide trusses or braces *p p* between the said tie-beam *D* and the car-body, and the compound beam-connected yokes at each side of the truck are united to 45 form the yoke or truck-frame by suitable transverse ties, beams, or girders—such, for instance as those provided at the ends of the truck at *E E* and those intermediately applied, as indicated at *F*, the latter serving, 50 when the truck is to be used for an electric car, as a partial support for the motor.

It will be noticed that the sill-plates and sills with the bolt-rods *l l l l* and the tie-beam *D*, which is preferably trussed, as aforesaid, 55 form a rigid frame, which is as a part of the car-body, and which is independently and vertically movable relative to the truck-frame, which latter is in turn cushion-supported from the axle-boxes or steps thereof, and the 60 car-body with the frame constituted by the bolt-rods and tie-beams are spring-supported, and may have the usual and comparatively considerable bounding motion from the yoke-frame and upon the supporting-frames *o o o* 65 *o*. All lateral, longitudinal, or tilting motions of the truck or yoke frame with relation to the journal-boxes are prevented by

the peculiar engagement of the said bolt-rods, and the tilting motion which the yokes of the truck-frame might have, resulting in a bind 70 between the apertures in the yokes and the bolt-rods, is materially lessened, due to the close arrangement which the said bolt-rods *l* have to the centers of the journal-boxes, which centers might serve as the centers of 75 tilting motion for the yokes.

The guards *J* are pivotally mounted on the brackets *t* pending from the yoke-extensions *a'*, whereby they may be swung up from their usual proximity to the trackway through 80 means of the chains *u* or other connections properly continued and actuated.

The transverse uniting members of the truck-frame *E*, as shown in the present drawings, consist of the angle-irons, which are 85 bolted to and extend transversely between the hangers *t*, which are at opposite sides of the truck-frame.

Having fully described our invention, what we claim, and desire to secure by Letters Patent, is—

1. The combination, in a truck, with the axle-boxes provided with the steps, of a yoke, cushion-supported from the axle-box and provided with extensions, springs which are applied longitudinally beyond said cushion-supports and between the yoke-extensions and the body of the car, and vertical posts or bolt-rods extended from the car-body downwardly and having an engagement, as described, with the said yoke and axle-box steps, for the purpose set forth.

2. The combination, with axle-boxes at one side of the truck, of united yokes supported thereon, the car-body spring-supported from 105 said yokes and provided with posts or bolt-rods having an engagement, as described, whereby there is only a vertical motion of said rods relative to said yoke, and the tie-beam *D*, uniting the posts and pairs thereof, 110 substantially as described.

3. The combination, with the axle-box provided with the steps *c c* vertically apertured, and the yoke-cushion supported from the said journal-box steps and vertically apertured, as 115 described, of the car-body having the sill-plate *C*, provided with the sockets 7 7, let in from the upper side thereof, and having toward the ends of said plate from said sockets the socketed bosses *n n*, the bolt-rods *l l*, by 120 their extremities entered and engaged in said sill-plate sockets 7 7, as described, and passed downwardly through the apertured yoke and axle-box steps, and the springs forwardly and rearwardly of said bolt-rods and between the 125 yoke-extensions and said socketed bosses *n n*, substantially as described.

4. In a truck, the combination, with the axle-box, of a yoke saddled thereon and provided with pairs of cheek-pieces forward of 130 and at the rear of the axle-box, and tie-braces *q q*, uniting side pairs of said cheek-pieces, substantially as described.

5. A yoke consisting of side pairs of cheek-

pieces, each side pair separated by the aperture *e*, said cheek-pieces merging into a hood or dome-shaped top for the yoke, horizontal supports or rests transversely uniting side 5 pairs of said cheek-pieces and forward and rearward extensions *a'* and *a²*.

6. In a truck, the combination, with an axle-box having steps *c c*, of a yoke consisting of side pairs of cheek-pieces, each side pair 10 separated by the aperture *e*, within which the axle-box proper is disposed, and between the lower portions of which cheek-pieces the axle-box steps are disposed, and the said cheek-pieces merging into a hood for the top of the 15 yoke for covering the axle-box, and the horizontal supports or rests *ff* above the axle-box steps, substantially as described.

7. In a truck, the combination, with an axle-box having steps *c c*, of a yoke consisting of 20 side pairs of cheek-pieces, each side pair separated by the aperture *e*, within which the axle-box proper is disposed and between the lower 25 portions of which cheek-pieces the axle-box steps are disposed, and the said cheek-pieces merging into a hood for the top of the yoke for covering the axle-box and the horizontal supports or rests *ff* above the axle-box steps and the cushions *g g* between the said steps and said rests, substantially as described.

30 8. A yoke consisting of side pairs of cheek-pieces, each side pair separated by the aperture *e*, the said cheek-pieces merging into a hood for the top of the yoke, the transverse web *j* and the rests *ff* transversely uniting side 35 pairs of said yokes, combined with the axle-box having the steps *c c*, and the cushions *i* and *g g*, substantially as described.

9. A yoke consisting of side pairs of cheek-pieces, each side pair separated by the aperture *e*, the said cheek-pieces merging into the 40 hood or dome-shaped top for the yoke, the transverse rests *ff*, and the forward and rearwardly extended extensions *a' a²*, all integrally cast, substantially as described.

45 10. In a truck, the combination, with the pair of axle-boxes at each side of the truck, each having the steps *c c*, provided with the

sockets *d*, yokes saddled on each journal-box, each consisting of side pairs of cheek-pieces separated by the aperture through which the 50 journal-box proper passes, said cheek-pieces merging into a hood forming the top of the yoke for covering the axle-box, and the horizontal supports or rests above said steps *c* and the forward and rearward extensions *a'* 55 *a²*, and a beam connecting side pairs of said yokes, and the cushions *g g*, of the car-body provided with the sill-plate, and the bolt-rods *ll* engaged therewith and extended downwardly through apertures in the top of the 60 yoke and in said rests *ff* and said steps, the springs *oo*, forward and to the rear of said bolt-rods and supporting the car-body from said yoke-extensions, and the tie-beams *DD* 65 uniting the bolt-rods of each pair and also uniting side pairs of said bolt-rods, all substantially as described, for the purposes set forth.

11. The combination, with a car-body provided with the pending bolt-rods *ll*, of the 70 axle-boxes and the yoke-frame supported thereon, and through which yoke the said bolt-rods pass, as described, the supporting-springs *oo* between the yoke-frame and the car-body, the tie-beams *DD* 75 uniting the bolt-rods, as described, and the brace or truss rods *pp* connected between said tie-beams and the car-body.

12. In a truck, the combination, with a suitable frame thereof, of a guard transversely 80 applied and pivotally connected on said truck-frame, and having a chain or other flexible connection secured thereto, whereby through said chain said transverse guard may be swung at will into and out of proximity to 85 the trackway, substantially as described.
